CLIP TO KEEP IN ENGAGEMENT THE ENDS OF SHOESTRINGS OR OTHER FASTENERS

Filed Nov. 18, 1940

Inventor

Howard P. Okie

UNITED STATES PATENT OFFICE

2,254,579

CLIP TO KEEP IN ENGAGEMENT THE ENDS
OF SHOESTRINGS OR OTHER FASTENERSHoward Pitcher Okie, Washington, D. C., assignor
of one-fourth to Benjamin S. Bell, Washington,
D. C., and one-fourth to Louise A. Green, Wash-
ington, D. C.

Application November 18, 1940, Serial No. 366,191

2 Claims. (Cl. 24—121)

This invention relates to clips and has for its object the construction of a device adapted to secure against casual, undesigned disconnection of the ends of laces, strings or ribbons used to keep together adjacent parts of shoes or other articles of dress, and, at the same time, to facilitate the disengagement of the ends of such fasteners, thus entirely obviating the necessity of tying or untying knots.

The invention is an improved article of manufacture of novel construction hereinafter described and claimed.

I have fully and clearly illustrated my improved device in the accompanying drawing, in which:

Figure 1 is a perspective view showing the clip in use; Figure 2 is a side elevation of the clip as it appears when not in use; the device is of two elements, and Figure 3 shows the contained, or inner, member; it is made of stainless, tempered steel and functions as a spring; Figure 5 is the containing element, or shell; it must be made of a rigid substance and I prefer to employ plastic phenolite as it may be of different colors and shades to make a harmonious effect; in this figure, O is an orifice to permit the emergence of the knob K as shown in Figure 3; DD in Figures 3, 4 and 5 are angular depressions made in the ceilings of each element so placed that when assembled the ridges in the under side of the ceiling of the shell will enmesh with the grooves in the roof of the inner or contained element. CC in Figure 5 are curved openings or slots to facilitate the placing of laces or strings between, re-

spectively, the ceiling of the container and the roof of the inner element; this act is performed while the two elements are temporarily separated at the top by depressing the knob K; before releasing that pressure the strings to be secured are drawn taut, they thus become chords of the arcs CC and will traverse the grooves of the contained member and will be tightly held in place when the pressure upon K is removed and the ridges and grooves tend to enmesh. Figure 4 is a cross section through the center of the projecting knob K of the device when assembled but is not in use; Figure 6 is a plan of the upper surface of the clip as it appears when in use.

Having fully described my invention, what I claim as new and what I desire to secure by Letters Patent is:

1. A fastener for shoe laces, cords and ribbons comprising a rigid shell having a wall provided with a pair of curved slots and an opening between the slots, an angular depression in said wall between said opening and each of said slots, and a resilient member within the shell having means adapted to register with said depressions and provided with a knob projecting through said opening.

2. A fastener for shoe laces, cords and ribbons comprising a rigid shell having a wall provided with a pair of curved slots and an opening between the slots, a resilient member within the shell and forming a clamp with said wall of the shell, and a projection on said resilient member disposed in said opening.

HOWARD P. OKIE.
